UNITED STATES PATENT OFFICE

EARLE M. CROSBY, OF BIRMINGHAM, MICHIGAN, ASSIGNOR, BY MESNE ASSIGNMENTS, TO UNITED-CARR FASTENER CORPORATION, OF CAMBRIDGE, MASSACHUSETTS, A CORPORATION OF MASSACHUSETTS

MACHINE FOR SORTING AND SETTING FASTENERS

Application filed December 9, 1926. Serial No. 153,549.

This invention relates to machines for handling metallic fasteners, and more especially to machines adapted to set or drive snap fasteners or parts of such fasteners. The invention will be herein disclosed as embodied in a machine for setting the socket members of snap fasteners, but for convenience the parts handled by the machine will be hereinafter referred to simply as "fasteners".

It is an important object of this invention to devise a simple and reliable mechanism for sorting or arranging the fasteners properly for delivery to the setting or driving mechanism.

In machines designed to set fasteners some distance inwardly from the edge of the work, as for example, on a rug, curtain, or the like, the increased width of throat required to permit the introduction of the work increases the difficulty of transferring the fasteners to the setting point with the desired speed and certainty. The present invention deals with this problem and it aims to devise a mechanism which will effect such a transfer rapidly and smoothly, regardless of the distance, and will reduce to a minimum the danger of breakage of the machine parts.

The nature of the invention will be readily understood from the following description when read in connection with the accompanying drawings, and the novel features will be particularly pointed out in the appended claims.

In the drawings,

Figure 1 is a vertical, cross-sectional view of a portion of a fastener setting machine constructed in accordance with this invention;

Fig. 2 is a side elevation of a Geneva drive which is used in the machine;

Fig. 3 is a view, partly in front elevation and partly in cross-section, showing the hopper and associated parts of the fastener sorting mechanism of the machine;

Figs. 4 and 5 are perspective and plan views, respectively, of the fasteners which the present machine is particularly designed to handle;

Fig. 6 is a cross-sectional view substantially on the line 6—6, Fig. 3;

Fig. 7 is a plan view of the screw conveyor for transferring the fasteners from the raceway to the setting mechanism;

Fig. 8 is a plan view on a larger scale of a portion of the mechanism shown in Fig. 7; 55

Fig. 9 is a cross-sectional view on the line 9—9, Fig. 8;

Fig. 10 is a plan view of a removable plate for the conveyor mechanism;

Fig. 11 is a front elevation of the driver 60 or plunger which sets the fasteners and the operating mechanism therefor;

Fig. 12 is a vertical cross-sectional view of the fastener hopper and associated parts;

Fig. 13 is a transverse, cross-sectional view 65 through the screw conveyor;

Fig. 14 is a front elevation of a section of the raceway for the fasteners;

Fig. 15 is a side elevation of the raceway section shown in Fig. 14; 70

Fig. 16 is a cross-sectional view on the line 16—16, Fig. 15;

Fig. 17 is a vertical, cross-sectional view of a modified form of fastener conveyor and the setting mechanism associated therewith; 75

Fig. 18 is a front elevation of the conveying mechanism shown in Fig. 17; and

Fig. 19 is a plan view of a portion of the conveying and setting mechanism shown in Fig. 17. 80

The machine shown comprises a hopper for sorting the fasteners, a raceway to which the sorted fasteners are delivered, a screw conveyor which transfers the fasteners from the raceway to the setting point, and a mechanism for setting or driving the fasteners delivered to it. The detailed description of the various mechanisms will be taken up in substantially the order in which they have just been mentioned. 90

As shown in Figs. 4 and 5, the type of fastener which the machine shown is particularly designed to handle consists of a spring socket member adapted to receive a suitable 95 stud. This member comprises an annular sheet metal body 2, slotted to give it the desired spring or snap, and provided with a series of prongs 3 projecting from the upper side thereof. In setting these fasteners the 100

prongs are forced through the material and then clinched.

The mechanism for sorting or arranging the fasteners properly for the setting operation comprises a hopper which includes a rotary bowl 4, Figs. 3 and 12, secured fast on an inclined shaft 5. This shaft is mounted in a bracket 6 which forms the bottom of the hopper. Secured to the lower edge of the bowl 4 is a ring 7 of angular cross-sectional shape, as best shown in Figs. 6 and 12, which forms, to all intents and purposes, a part of the bowl and rests on the upper surface of the hopper bottom or bracket 6. A series of webs 8, Fig. 12, connects the wall of the bowl with the central sleeve 9 in which the shaft 5 is secured, these webs being separated by wide apertures or spaces through which the fasteners can be dumped into the hopper. The fasteners fall by gravity against the lower wall of the hopper and tumble around freely as the bowl 4 is rotated slowly.

In order to permit the escape of the fasteners from the hopper, the ring 7 is provided with a series of passages or guideways 10 of suitable dimensions to permit the fasteners to pass freely through them. It is desirable to deliver the fasteners to the setting mechanism with their prongs pointing upwardly, and for the purpose of permitting the passage of those fasteners positioned in this manner and rejecting those which are wrong side up, each passage 10 is provided with a stop in the form of a pin 12, Fig. 12, which projects from the top downwardly toward the bottom of each guideway. The end of each pin, however, is spaced far enough from the bottom of the guideway to permit the body 2 of a fastener to pass freely under it, the prongs 3 dodging the pin. The pin, however, effectually prevents the passage of any fastener in an inverted position; that is, with its prongs pointing downwardly.

As the hopper rotates slowly in a counter-clockwise direction, Fig. 3, fasteners which are positioned right side up slide into the guideways 10 and past the pins 12, their complete passage through the guideways, however, being blocked by a flange projecting upwardly from the margin of the hopper bottom 6 until they have been carried around past the end of this flange at approximately the point 13, Fig. 3. Those fasteners which have passed the pins 12 can then slide into the upper section 14 of the raceway. This part of the raceway is formed in the right hand margin, Figs. 3 and 6, of the hopper bottom 6, and the fasteners are prevented from jumping out of this raceway by an overlying guard or plate 15.

The upper section 14 of the raceway terminates just below the middle of the hopper bowl at the point 16, Figs. 3 and 12. In order to conduct the fasteners from this raceway to the conveying mechanism, another

raceway section 17 is provided which preferably is made removable, this raceway section being best shown in Figs. 1, 14, 15 and 16. It comprises a lower member 18 of U or channel section, and an upper plate-like member 20 closing the groove or channel in the lower member, the channel being deep enough to permit the fasteners to slide freely through the raceway. One side wall of the lower member 18 is cut away for some distance to provide a slot 21 which permits inspection of the fasteners as they slide through the raceway so that if they should become jammed, that fact can easily be determined. It also permits the introduction of an implement to release a jammed fastener.

This removable raceway section is releasably secured to the upper raceway section 14 by means of a slidable latch or clip which includes a spring piece 22, carried by a U-shaped slide 23 which embraces the raceway and is held thereon by a screw 24. The upper end of the spring 22 is curved to engage a groove or socket 25, Fig. 12, formed in the lower side near the end of the upper raceway. Normally this clip or latch is in the position shown in Fig. 1 where it holds the lower raceway section 17 in its operative position. By sliding the latch 22 downwardly along the raceway, as shown in Fig. 15, the removable raceway section 17 may be released from the upper section 14 and it can then be taken out of the machine.

For the purpose of transferring the fasteners from the lower end of the raceway to the setting point, a conveyor is provided which comprises a screw 27, preferably having square threads, and these threads are spaced apart by a sufficient distance to accommodate fasteners between them. The screw is supported horizontally by a driving shaft 28 at one end, its opposite end resting in a socket formed in the upper part of a bearing bracket 30. It is driven intermittently by a Geneva movement which includes a Geneva wheel 31 fast on the shaft 28 and a Geneva driver 32 fast on the main driving shaft 33. The latter shaft is equipped with a pulley 34 so that it may be belted to any convenient source of power. This mechanism gives the screw 27 a quarter revolution for each complete revolution of the main shaft 33.

Cooperating with the screw 27 are two guides 34-34, Figs. 7 and 13, which extend the entire length of the screw and are located above it, the guides being separated to provide a straight slot or passage 19 for the fasteners, this slot leading from the lower end of the raceway 17 to the setting mechanism. As the lowermost fastener 2 in the raceway 17 slides forward on to the screw 27, its motion is arrested partly by engagement with one of the threads of the screw and partly by a spring pressed dog 35, Figs. 7 and 8, which prevents the fastener from overrunning. A

fastener so positioned is advanced at each quarter revolution of the screw by a distance equal to the space between the threads of the screw, so that as soon as the machine has made a few revolutions each space between threads is occupied by a fastener 2, as shown in Fig. 7. Thereafter each quarter turn of the screw 27 feeds one fastener forward to the plunger or driver 36 of the setting mechanism.

In order to prevent the fasteners 2 from jumping out of the conveyor guideway 19, a plate 37 is removably secured to the guides 34-34, as best shown in Figs. 1 and 13, where it will overlie the fasteners as they are transferred by the conveying screw 27. At its end adjacent to the raceway this plate is slotted to provide a central tongue 38, Fig. 10, the free end of which will have considerable resiliency. If for any reason a fastener should be caught on a thread of the screw as the fastener emerges from the raceway, such a fastener would simply be pressed upwardly against the tongue which would spring sufficiently to prevent breakage of any of the parts. The plate 37 has a dovetail connection with the guides 34-34 so that it can be removed by an endwise movement. It will be observed that the guides 34-34 hold the fasteners on the screw where they are supported by it as they travel from the lower end of the raceway to the setting mechanism.

The setting mechanism for the machine is best shown in Figs. 1 and 11, and comprises a driver or plunger 36 normally held down by a spring 40 and arranged to be given its upward or driving stroke by means of a cam 41 acting on a roll 42 which is carried by the driver 36. The stroke so imparted to the driver carries the fastener supported on its upper end upwardly against an anvil 43 which is slidably mounted in the overhanging head 44 of the machine but is held down by a strong spiral spring 45. The tension of this spring can be adjusted by a screw 46.

Preferably the machine is driven through a single revolution clutch which is controlled by a foot treadle, knee lever, or the like, so that when the operator places the work in the machine and steps on the treadle, the machine will make one complete cycle, driving a single fastening, and will then stop automatically.

As shown in Figs. 1 and 12, the hopper is driven from the main shaft by a belt 48 driven from a combined pulley and hand wheel 50 on the main shaft 33 and driving a pulley 51 fast on the hopper shaft 5.

In order to prevent breakage of the parts in case the screw 27 becomes jammed for any reason, an automatically releasable connection is provided in the driving mechanism for this screw. As shown in Fig. 1, this mechanism comprises a collar 52 carrying pins 53-53 which project loosely into holes formed in the solid portion of the screw near

its right-hand end. This collar also is provided with a V-shaped notch 54 to receive a similarly shaped projection 55 extending from a second collar 56 which lies immediately beside the collar 52. An extension 57 of the shaft 28 projects loosely through both collars and is encircled by a spring 58 which presses the collar 56 against the collar 52, the spring being backed up by a washer and a nut 60 threaded on to the end of the shaft 57. If the screw 27 should encounter any abnormal resistance to its rotative movement, or be subjected to any severe overload, the projection 55 would slip out of the notch 54, thus releasing or interrupting the driving connection between the two parts 56 and 52. This release permits the shaft 28 to revolve without driving the screw. Any other suitable mechanism of this type may, however, be substituted for that shown.

It will be observed from an inspection of Fig. 1 that the machine has a wide or deep throat so that fasteners can be inserted in a rug, curtain, or the like, well back from its edge, as frequently is desirable. At the same time the difficulties introduced by the fact that such a throat construction necessitates the feeding or transfer of the fasteners for a considerable distance beyond the point to which they are fed by gravity, is effectually solved by the screw conveyor. Each quarter turn of the screw delivers a fastener to the setting mechanism and this would be equally true if the screw were longer or shorter. The mechanism works positively and at the same time very smoothly. The necessity for long stroke reciprocating plungers or the like, therefore, is avoided, and the difficulties incidental to their use, and the fact that they must be operated at relatively high speeds in order to give the desired output, also are avoided.

It will be understood that the movements of the screw 27 and the driver or plunger 36 of the setting mechanism are so timed that in each cycle of operations of the machine the screw will first deliver a fastener to the driver and then the driver will be operated to drive or set the fastener in the work, the screw in the meantime remaining stationary. Due to the fact, however, that the fastener transferring movement which takes place in each cycle is very short, the portion of the cycle required to effect this movement is correspondingly short, and the machine can, therefore, be operated at relatively high speeds while still operating smoothly and positively.

As has been stated, the mechanism above described has been designed with particular reference to the requirements of a certain type of fastener. It is contemplated, however, that mechanisms embodying the essential features of this invention can also be used to advantage in handling other types of

fasteners. In feeding some kinds of fasteners, the fact that the walls of the slot or passage 19 through which the fasteners are guided is some little distance above the surface of the screw 27, may be objectionable in tending to cause the fasteners to become cramped or jammed between the screw and the guides. In such cases, therefore, we prefer to use the construction shown in Figs. 17, 18 and 19. Referring to these figures it will be observed that the threads of the screw 27' are slotted transversely to the axis of the screw so that each thread is, in effect, composed of a series of teeth 62. The guides 34'-34' which cooperate with the screw are made of relatively thick stock and their lower surfaces are milled to accommodate the teeth 62. This construction provides projections or teeth 63 on the guides 34' which enter the slots that separate the teeth 62 of the screw 27', the teeth 63 extending down close to the bottoms of the slots, as shown in Fig. 18. The two guides 34'-34' are spaced apart to provide a passage or slot 19' between them through which the fasteners 64 are advanced or fed by the screw 27'. The particular type of fastener shown in Figs. 17, 18 and 19 has a relatively large head with a reduced shank, and accordingly, the guiding surfaces of the parts 34'-34' are shaped to accommodate this particular fastener. If the fastener were of a different shape it might be necessary or desirable to make the guiding surfaces of the parts 34' of a somewhat different shape.

The slotted and toothed construction of the guides 34' and the threads of the screw 27' prevent any possibility of fasteners becoming jammed between the screw and the guides, and it enables the screw to feed fasteners which could not be handled by the construction previously described. For example, very thin fastener members, such as socket plates, or washers, can be fed successfully with the mechanism shown in Figs. 17, 18 and 19.

While I have herein shown and described the best embodiments of my invention that I have so far devised, it will be understood that the invention may be embodied in other forms without departing from the spirit or scope thereof.

Having thus described my invention, what I desire to claim as new is:

1. In a machine for handling fasteners, a mechanism for transferring fasteners comprising a screw conveyor having its threads slotted transversely to the axis thereof, and guiding means for said fasteners having projections extending into the slots in said threads.

2. In a machine for handling fasteners, a mechanism for transferring fasteners comprising a screw having threads spaced apart axially to receive fasteners between them, said

threads being slotted transversely to the axis of the screw, guiding means associated with said screw and having a slot extending longitudinally of the screw, through which slot said fasteners are propelled by the screw, said guiding means having projections extending into the slots in said threads, and mechanism for rotating said screw. 70

3. In a machine for setting fasteners, the combination of setting means, a screw for delivering fasteners to said means, guides associated with said screw for guiding the fasteners longitudinally thereof but holding the fasteners on and supported by the screw, a removably mounted plate overlying the series of fasteners supported on said screw, and means for imparting a step by step rotative movement to said screw. 75

4. In a machine for setting fasteners, the combination of setting means, a screw for delivering fasteners to said means, guides associated with said screw for guiding the fasteners longitudinally thereof, said screw being hollow, a driving shaft extending into said screw, driving connections between said shaft and said screw including means for automatically interrupting the driving relationship under abnormal resistance to the rotation of the screw, and means for giving said shaft a step by step rotative movement. 80

5. In a machine for setting fasteners of the type having a head with one or more projections extending from one side of said head transversely to the plane of the head, the combination of a hopper for holding a supply of said fasteners, an inclined raceway to which the fasteners are delivered by said hopper with the heads of the fasteners resting on the raceway, mechanism for setting said fasteners, a screw for receiving said fasteners from said raceway and delivering them to said setting mechanism, guides associated with said screw for guiding the fasteners longitudinally thereof while the heads of said fasteners rest on said screw, and means operating in timed relationship to the operation of said setting mechanism for giving said screw a step by step rotative movement to cause it to deliver a single fastener to said setting mechanism in each cycle of operations of said machine. 100

6. In a machine for setting fasteners of the type having a head with one or more projections extending from one side of said head transversely to the plane of the head, the combination of a hopper for holding a supply of said fasteners, an inclined raceway to which the fasteners are slidably delivered by said hopper with the heads of the fasteners resting on the raceway, mechanism for setting said fasteners, a screw to which said raceway conveys said fasteners by gravity, means (35) at the discharge end of the raceway for positioning the lowermost fastener for transfer to said screw, said screw serving to de- 110

liver fasteners so received to said setting mechanism, and means operating in timed relationship to the operation of said setting mechanism for rotating said screw to cause it to deliver a single fastener to said setting mechanism in each cycle of operations of the machine.

7. In a machine for attaching snap fastener members, a setting means, a chute for snap fastener members terminating at a substantial distance from said setting means, a guiding means, a rotary screw conveyor located in the space between the setting means and the end of the chute and operable to impel the fastener members from the end of the chute and deliver them one at a time directly to the setting means, a shaft upon which said screw conveyor is mounted, and a clutch mechanism located between the shaft and the conveyor, said clutch mechanism being constructed and arranged to permit relative movement between the screw conveyor and the said shaft if the said conveyor becomes jammed.

25 In testimony whereof I have signed my name to this specification.

EARLE M. CROSBY.
